ANIMAL SHELTER

James L. Artig, White Bear Lake, Minn., assignor to Artig Products, Inc., a corporation of Minnesota

Filed Oct. 7, 1966, Ser. No. 4,202

Term of patent 14 years

(Cl. D30—1)

FIG. 1

FIG. 2

FIG. 3

FIG. 5

FIG. 1 is a perspective view of the shelter;
FIG. 2 is a front elevational view;
FIG. 3 is a right hand side elevational view;
FIG. 4 is a top plan view of the shelter in FIG. 2; and
FIG. 5 is a top plan view of the shelter in FIG. 4 with the top removed.

The rear of the shelter is a mirror image of FIG. 2
and the left hand side view of FIG. 2 is a mirror image of FIG. 3.

I claim:

The ornamental design for an animal shelter, as shown and described.
